(57) **CLAIM**

The ornamental design for a camping tub and sink assembly, as shown and described.

DESCRIPTION

FIG. 1 shows a perspective view of the camping tub and sink assembly.

FIG. 2 shows a front view of the camping tub and sink assembly.

FIG. 3 shows a rear view of the camping tub and sink assembly.

FIG. 4 shows a side view of the camping tub and sink assembly.

FIG. 5 shows an opposing side view of the camping tub and sink assembly.

FIG. 6 shows an overhead view of the camping tub and sink assembly; and,

FIG. 7 shows an underside view of the camping tub and sink assembly.

The broken lines shown in the drawing views represent unclaimed portions of the sink assembly and form no part of the claimed design.
